SHUTTLE

Horace H. Burdett, Milford, Mass., assignor to
Draper Corporation, Hopedale, Mass., a corpora-
tion of Maine

Application May 11, 1939, Serial No. 273,065

10 Claims. (Cl. 139—207)

The present invention pertains to loom shuttles and more particularly relates to the construction and mounting of the bobbin gripping spring of such shuttles.

5   Shuttles of the type to which my invention applies commonly include a shuttle body having a bobbin receiving cavity and a spring receiving recess at one end of such cavity, a bobbin gripping spring having opposed jaws located in the 10 cavity and a shank portion seated in the recess, and fastening screws for holding the spring in the shuttle body. Prior constructions were such that to hold the spring against lateral movement reliance was had on a tight fit of the shank 15 of the spring in the recess therefor in the shuttle body, and on friction between the spring and the top and bottom plates of a cover member. In such constructions, an enlargement of the spring receiving recess by wear or expansion of 20 the wood of the shuttle results in the spring becoming loose. Such prior constructions are subject to the further disadvantage that with use the spring sags downward and thereby objectionably lowers the tip of the bobbin. No 25 prior adjusting means to correct this latter defect, of which I am aware, has been successful or used commercially.

A principal object of the present invention is to provide a loom shuttle comprising a shuttle 30 body with a cavity and recess, a shuttle spring, and fastening screws, as aforesaid, and means, actuated by a horizontal screw passing transversely through the shuttle body and the shank of the spring, for clamping the shank laterally 35 against one side wall of the recess, to thereby prevent the spring from becoming loose when the recess becomes enlarged.

A further object is to provide, in a shuttle as aforesaid, novel and practical means for vertically 40 adjusting the bobbin gripping jaws of the shuttle spring to thereby properly position the tip of the bobbin in the shuttle.

The foregoing and other objects of the invention are accomplished in the construction illus- 45 trated on the accompanying drawing, of which:

Fig. 1 is a plan view of one end of a shuttle having the preferred embodiment of my invention applied thereto;

Fig. 2 is a horizontal sectional view of the same; 50 Fig. 3 is a view in cross-section taken approxi- mately on line 3—3 of Fig. 1; and

Fig. 4 is a detail view, in perspective, showing the adjusting bushing used in said preferred embodiment.

55   The shuttle shown on the drawing comprises

a shuttle body 1 of the usual size and shape, having the usual cavity 2 therein for receiving a bobbin 3 which is adapted to carry the filling supply used in weaving. The thread delivery end of the shuttle is of any suitable usual construction and is accordingly not shown or described. The end of the shuttle shown carries a bobbin gripping spring for releasably holding the bobbin 3 by the butt portion 4 thereof, which spring is supported in the shuttle body in accordance with the present invention.

As shown, the aforesaid bobbin gripping spring comprises a shank portion 5 and bobbin gripping portions in the form of jaws 6. The shuttle body 1 has a recess 7 at one end thereof communicating with the cavity 2, which recess has parallel vertical side walls 8 extending longitudinally of the shuttle. The shank portion 5 of the spring is seated in this recess preferably with a tight fit. The jaws 6 project from the recess 7 into the cavity 2 on opposite sides of the bobbin butt and are of spring steel construction to releasably grip the bobbin. The shank portions of the jaws may be integrally joined as at 9.

The shuttle construction shown includes a conventional form of spring cover, so-called, which consists of a strip of metal bent to form a top plate 10, an inclined bobbin guide portion 11 and a bottom plate 12. The plate 12 rests on the floor 13 of the recess 7, the spring shank rests on the plate 12, and the top plate 10 engages the top of the spring shank. The spring cover and the spring are held together by a vertical fastening member in the form of a screw 14 which passes through the top and bottom plates 10 and 12 and between the shank portions 5. This assembly is held in the shuttle body 1 by a horizontal fastening member such as screw 15 which passes transversely through the shuttle body and the shank portion 5 of the spring.

The shuttle body, bobbin gripping spring and spring cover as thus far described in detail are of usual construction, the changes which I have made in such parts being hereinafter described. 45 It will be noted that, in common with prior constructions, the shuttle spring in a new shuttle is held against lateral movement by the walls 8 of the recess 7. Also, the jaws 6 are held in proper vertical position by the plate 12 resting on floor 13 of the recess. Thus, when the recess 7 becomes enlarged by wear or from other cause the spring shank becomes loose in the recess and in the absence of other holding means the spring would be free to move laterally. Also, wear of 55

the floor 13 and other parts will allow the jaws 6 to drop down, thereby lowering the tip of the bobbin 3 from its proper position.

In prior constructions, the aforesaid loosening of the shuttle spring and lowering of the tip of the bobbin have been of serious consequence, and the problems of preventing or correcting the same have been vexatious and long standing. As will appear, I have solved such problems in a simple and practical manner.

The problem of preventing the shuttle spring from becoming loose in the shuttle body is solved by providing means for clamping the shank of the spring against one of the vertical walls of the recess, so that the spring is held tightly regardless of the size of the recess. In a shuttle of the particular construction shown on the drawing, the shank portion 5 is clamped against one of the vertical walls 8 by a metallic clamping member which may be carried by and is acted upon by the fastening member or screw 15. In the preferred embodiment, said clamping member consists of a bushing 16.

The bushing 16 is generally tubular in form and the hole 17 therethrough is of the proper size to loosely receive the screw 15. The bushing is positioned on the screw with the end 18 of the bushing engaged by the head 19 of the screw either directly or through the means of intervening washers 20 as may be desired. The bushing 16 is provided with a shoulder 21 which extends around the screw 15 and bears against the shank 5 of the spring. When the screw 15 is tightened, the bushing 16 is acted upon by the head of the screw to force the shoulder 21 against the shank 5 of the spring and thereby clamp the latter against the opposite wall 8 of the recess 7, thereby holding the spring tightly regardless of the size of the recess.

The prior difficulties caused by the lowering of the bobbin gripping jaws are overcome by the provision of practical and efficient means for adjusting the vertical position of the jaws. In accordance with my invention, the adjusting means is carried by the horizontal holding screw for raising and lowering the bobbin gripping jaws, the adjustment preferably being about an axis parallel to such holding screw.

In the particular embodiment shown, the aforesaid adjusting means, consists of an eccentric bushing, formed by providing an extension 22 on the bushing 16. The extension 22 is eccentric with relation to the external periphery of the bushing 16 and with relation to the hole 17 therethrough. This eccentric portion 22 extends through and is journalled in a hole in the shank portion 5. The spring is arranged to rock about an axis which is parallel to the screw 15, and to this end the lower edge of the shank portion 5 is beveled or tapered at 23, Fig. 3, to provide a fulcrum edge 24. This edge 24 extends transversely of the shank portion 5 and rests on the plate 12, whereby the spring may rock on the plate. The bushing 16 may be provided with a screw driver slot 25 for convenience in turning the bushing.

In the embodiment shown, if through wear or other cause the jaws 6 drop too low, the screw 15 is removed (leaving the bushing 16, 22 in place) and the bushing is turned slightly by means of a screw driver engaged with slot 25. This turning of the bushing raises the jaws 6 by rocking the spring, counterclockwise on Fig. 3, about the axis 24. Then, when the screw 15 is replaced it will firmly hold the bushing and spring in adjusted position.

Having fully disclosed the preferred embodiment of my invention, I claim:

1. A loom shuttle comprising a shuttle body having a bobbin receiving cavity and a recess communicating with said cavity, said recess having longitudinally extending side walls, a bobbin gripping spring having a shank portion seated in said recess, a horizontal fastening member passing transversely through said shuttle body on both sides of said recess and through said shank portion, and means carried by said fastening member and actuated thereby for clamping said shank portion against one of said side walls of said recess.

2. A loom shuttle comprising a shuttle body having a bobbin receiving cavity and a recess communicating with said cavity, said recess having longitudinally extending side walls, a bobbin gripping spring comprising a shank portion seated in said recess and opposed gripping portions projecting into said cavity, a horizontal fastening screw passing transversely through both sides of said shuttle body and through said shank portion for fastening said spring in said shuttle body, and means carried by said screw and actuated thereby to clamp said shank portion against one of said side walls of said recess.

3. A loom shuttle comprising a shuttle body having a bobbin receiving cavity and a recess at one end of said cavity, said recess having substantially parallel longitudinal side walls, a bobbin gripping spring comprising opposed spring jaws having integrally joined shank portions seated in said recess and gripping portions projecting into said cavity, a screw member passing transversely through said shuttle body and shank portions for fastening said spring in said shuttle body, and a metallic clamping member actuated by said screw member to clamp said shank portions against one of said side walls of said recess.

4. A loom shuttle comprising a shuttle body having a bobbin receiving cavity and a recess communicating with said cavity, said recess having longitudinally extending side walls, a bobbin gripping spring having a shank portion seated in said recess, a horizontal fastening screw passing transversely through said shuttle body and said shank portion, and a member having a shoulder extending around said screw and bearing against said shank portion, said screw being arranged to force said shoulder against said shank portion to thereby clamp the latter against one of said side walls of said recess.

5. A loom shuttle comprising a shuttle body having a bobbin receiving cavity and a recess at one end of said cavity, said recess having longitudinally extending side walls, a bobbin gripping spring comprising a shank portion seated in said recess and opposed gripping jaws projecting into said cavity, a horizontal fastening screw passing transversely through said shuttle body and said shank portion, and a bushing on said screw, said bushing acting on said shank portion and being engaged by the head of said screw to thereby clamp said shank portion against the opposite side wall of said recess when said screw is tightened.

6. A loom shuttle comprising a shuttle body, a bobbin gripping spring having a shank portion seated in a recess at one end of said shuttle body, a horizontal fastening screw passing transversely through said shuttle body and said shank portion for fastening said spring in said shuttle body, and a bushing on said screw, said

- bushing having a shoulder bearing against said shank portion and an end engaged by the head of said screw to thereby clamp said spring in said recess when said screw is tightened.
5. 7. A loom shuttle comprising a shuttle body, a bobbin gripping spring having a shank portion seated in a recess at one end of said shuttle body, a horizontal fastening screw passing transversely through said shuttle body and said shank portion for fastening said spring in said shuttle body, said spring being mounted for adjustment about an axis parallel to but spaced from said screw, and means on said screw for adjusting said spring about said axis.
10. 8. A loom shuttle comprising a shuttle body, a bobbin gripping spring having a shank portion seated in a recess at one end of said shuttle body, a horizontal fastening screw passing transversely through said shuttle body and said shank portion for fastening said spring in said shuttle body, said spring being arranged to rock about an axis parallel to said screw, and an eccentric bushing on said screw for adjusting said spring about said axis.
15. 9. A loom shuttle comprising a shuttle body having a bobbin receiving cavity and a recess at one end of said cavity, a plate member at the bottom of said recess, a bobbin gripping spring

comprising a shank portion seated in said recess and opposed gripping jaws projecting into said cavity, said shank portion being fulcrumed on said plate, a horizontal fastening screw passing transversely through said shuttle body and said shank portion, and an eccentric bushing on said screw for adjusting said spring about said fulcrum.

20. 10. A loom shuttle comprising a shuttle body having a bobbin receiving cavity and a recess at one end of said cavity, said recess having side walls and a floor, a plate member on said floor, a bobbin gripping spring comprising a shank portion seated in said recess and opposed gripping jaws projecting into said cavity, the lower edge of said shank portion being tapered to provide a transverse fulcrum edge resting on said plate, a horizontal fastening screw passing transversely through said shuttle body and said shank portion, and an eccentric bushing on said screw for adjusting said spring about said fulcrum, said bushing having a shoulder engaging one side of said shank portion and an end engaged by the head of said screw to thereby clamp said shank portion against the opposite side wall of said recess.
